(57) **CLAIM**

We claim the ornamental design for a golf club ferrule, as shown and described.

DESCRIPTION

FIG. 1 is a perspective view of a golf club ferrule, showing a first embodiment of our new design;

FIG. 2 is an enlarged, exploded perspective view of FIG. 1, showing two identical, mating golf club ferrule halves;

FIG. 3 is a front elevational view of FIG. 1;

FIG. 4 is a rear elevational view of FIG. 1, one of the golf club ferrule halves omitted for clarity of illustration;

FIG. 5 is a left-side elevational view of FIG. 4, the right-side elevational view being a mirror image thereof;

FIG. 6 is a top plan view of FIG. 4;

FIG. 7 is a bottom plan view of FIG. 4;

FIG. 8 is a perspective view of a second embodiment thereof;

FIG. 9 is an enlarged, exploded perspective view of FIG. 8, showing the two identical, mating golf club ferrule halves;

FIG. 10 is a front elevational view of FIG. 8;

FIG. 11 is a rear elevational view of FIG. 8, one of the golf club ferrule halves omitted for clarity of illustration;

FIG. 12 is a left-side elevational view of FIG. 11, the right-side elevational view being a mirror image thereof;

FIG. 13 is a top plan view of FIG. 11; and,

FIG. 14 is a bottom plan view of FIG. 11.

The broken lines showing a golf club in FIGS. 1-2 & 8-9 depict environmental matter and form no part of the claimed design. The shading on the outer surface of the second embodiment is understood to represent any color except black.
